UNITED STATES PATENT OFFICE.

LEWIS C. SMITH, OF NEW YORK, N. Y.

DOOR-SECURER.

No. 880,108.

Specification of Letters Patent.

Patented Feb. 25, 1908.

Application filed April 26, 1907. Serial No. 370,387.

To all whom it may concern:

Be it known that I, LEWIS C. SMITH, a citizen of the United States, residing at New York city, in the county of New York, State 5 of New York, have invented certain new and useful Improvements in Door-Securers; and I do hereby declare the following to be a full, clear, and exact description of the invention, such as will enable others skilled in the art to 10 15 20 which it appertains to make and use the same.

This invention relates to fasteners and more particularly to door securers, and has for its object to provide a burglar-proof locking device of this nature, by means of which a door may be held against opening from the outside, and which will be arranged for adjustment to suit different conditions.

Another object is to provide a securer 20 which may be manufactured at a low figure.

In the drawings forming a portion of this specification and in which like numerals of reference indicate similar parts in the several views, Figure 1 is a sectional view of a portion of a door and the frame thereof, the present invention being illustrated in use in connection therewith. Fig. 2 is a perspective view of the complete fastener.

Referring now to the drawings, the present 30 invention comprises a plate 5 having an enlarged rounded portion 6 at one end and having a laterally-extending finger 8 at its opposite end, the plate being longitudinally slotted, as shown at 7, between its rounded 35 portion and its finger.

Formed longitudinally through the rounded portion there is a threaded passage 9, which communicates with the slot 7 and engaged in this passage there is a set-screw 10 40 having a flattened finger-piece 11 at its other end.

A member 12 is provided which is in the form of an elongated block and this block is formed at one corner thereof with a plurality 45 of stepped notches therein, as shown at 13, the sides of these notches extending at right-angles to each other and parallel with the corresponding edges of the member. Formed at the long side of the block which joins the 50 notched surface, and at the opposite end of this side from the notched surface there is a transversely-broadened portion 14 which, in practice, rests against the door.

In use, the finger 8 is inserted in the latch- 55 receiving recess *a* of a door-frame, and the door is then closed against the plate 5. The

member 12 is then inserted in the slot 7 with its broadened portion 14 resting against the door and the set-screw 10 is then operated to clamp the member securely in position.

60

It is a well-known fact that the face plate *b*, which is secured to the door-frame and which has the openings *c* through which the latch and bolt of a lock pass to secure the door, generally extends slightly beyond the 65 side of the door-frame, which lies in the direction in which the door swings open, this projecting portion of the plate receiving thereagainst the beveled face of the door-latch, and the notches 13 are disposed to receive this outwardly projecting portion of the face plate to give the member 12 an even bearing surface at both sides of the plate 5, and the plurality of notches 13 is provided 70 so that the member may be adjusted to suit 75 face plates extending at different distances beyond the door frame.

While the invention has been described and illustrated in connection with a door and its frame, it is to be understood that it may 80 be applied with equal facility to a window, and forms, in either instance, a keyless lock which is practically burglar-proof.

What is claimed, is—

A door securer comprising a plate having 85 an enlarged portion at one end and having a laterally-extending finger at its opposite end, said plate having a longitudinal slot between its enlarged portion and finger, said enlarged portion having a threaded longitudinal passage formed therethrough communicating with the slot, a member engaged in the slot and extending oppositely beyond the plate, said member having a broadened portion at one end and at its side which lies 90 in the direction of the finger and having its corner at its opposite end from the broadened portion in the direction of the finger cut away at an angle, the resulting slanting face being notched, and a screw engaged in the 95 threaded passage and impinging against the member, said finger being adapted for engagement in the opening of a door-frame face plate, and said member being adapted to receive an edge of said face plate in its 100 notches interchangeably.

In testimony whereof I affix my signature, in presence of two witnesses.

LEWIS C. SMITH.
